BY Victor J. Evans

ATTORNEY

UNITED STATES PATENT OFFICE

HARRY H. FERRIS, OF LOS ANGELES, CALIFORNIA

CALCULATING DEVICE

Application filed December 13, 1926. Serial No. 154,553.

This invention has particular relation to calculating devices to determine the pitch and length of common rafters when the rise and run is given.

5 Another object contemplates clamping members carried by a square and supporting the calculating device at appropriate points thereon for effecting the calculation.

More specifically stated, one of the clamping members embodies means operable in conjunction with the calculating device to correctly determine the pitch of rafters.

With the above and other objects in view, the invention further includes the following 15 novel features and details of construction, to be hereinafter more fully described, illustrated in the accompanying drawings and pointed out in the appended claim.

In the drawings:—

20 Figure 1 is an elevation of the invention applied for use upon the conventional form of square.

Figure 2 is a similar view of the calibrated clamping member.

25 Figure 3 is an end elevation thereof.

Figure 4 is an end elevation of an additional clamping member operable in conjunction with the remaining end of the calculating member.

30 Referring to the drawings in detail, wherein like characters of reference denote corresponding parts, the reference character 10 indicates the conventional form of builder's or carpenter's steel square. Slidably mounted

35 upon the vertical leg of the square is a clamping member 11 including a set screw 12 extending within a slot 13 for engagement with said vertical leg. An enlarged portion 14 is carried upon the inner side edge of the clamping member and adjacent the lowermost corner thereof and provided with a cut-out portion 15, the purpose of which will be readily apparent.

40 A clamping member 16 of a general configuration similar to that of the clamping member 11 is slidably mounted upon the horizontal leg of the square and adapted to be locked in a desired adjusted position after the manner of the clamping member 11. An arcuate shaped scale 17 is carried upon one side

edge of the clamping member 16. An enlarged portion 18 carried by the upper left hand corner of the clamping member 16 is provided with an opening 19 whose side walls flare oppositely and outwardly from a point 55 substantially central of the opening.

A calculating member consisting of an arm 20 marked off in inches and twelfths, to be subsequently referred to as feet and inches, has the upper end thereof pivotally mounted within the cut-out portion 15 of the enlarged portion 14 carried by the clamping member 11. The remaining end of the calculating device is disposed through the opening 19 and across the face of the arcuate shaped scale 60 65 17. Said scale is calibrated to indicate the rise in inches per foot run.

If the run were $11\frac{1}{2}$ feet and the rise $7\frac{1}{2}$, the respective clamping members would be disposed in registration with the inch markings upon the square. Said inch markings will now be considered as feet. Extensions 21 carried by each of the clamping members and disposed over the markings upon the square are divided into twelve divisions; each 70 75 division representing one inch.

When the clamping members are disposed in the manner as illustrated in Figure 1 of the drawing the length of the common rafter will be calculated upon the arm 20 immediately behind the enlarged portion 18, the length being 13 feet 8 inches. The distance between the pivot point for the arm and the exposed portion of the arm extending therefrom is equivalent to the distance from the center 80 85 of the opening within which the set screw 22 is threaded within the enlarged portion 18 to the rear edge of the latter. The length of the common rafter will thus be indicated in feet between 13 and 14 and the portions of a foot will be read upon the extensions 21. The reverse side of the plate 20 may be provided with indicia for calculating the length of hip and valley rafters to correspond to the common rafter found by the calculating device. The reading for hip and valley rafters is upon the reverse side of the arm 20 at the point said arm enters the opening 19. That portion of the arm 20 extending across the arcuate shaped scale 17 will correctly indi- 90 95 100

95 100

cate the pitch of the rafter in the same calculation. The difficulty as generally experienced in the calculation of the length of rafters and pitch thereof has been the reduction of inches ordinarily calculated in sixteen sections to twelve. In the application of the present invention the inches are considered as feet and the sections of the feet are considered as twelfths. The said twelfths are indicated upon the extensions 21. A set screw 22 is carried by the enlarged portion 18 of the clamping member 16 and adapted for biting engagement with the adjacent portion of the arm 20 to permit an operator to set the instrument while calculating the length of the rafter and pitch.

Squares of the character described are generally provided with calculations upon the reverse sides thereof to give the pitch of a rafter in degrees, namely, an eight inch rise on twelve would be three-fourths; the present invention overcomes the necessity of referring to the reverse side of the square which is often impossible when the square lies flush with a plate and rafter.

The invention is susceptible of various changes in its form, proportions and minor details of construction, and the right is herein reserved to make such changes as properly fall within the scope of the appended claim.

Having thus described the invention what is claimed is:—

A rafter measuring device adapted for use in conjunction with a square comprising clamping members provided with slotted portions adapted to permit sliding movement upon the legs of the square, set screws carried by the clamping members and projecting within the slotted portions and being adapted for engagement with the adjacent edges of the square legs to retain the clamping members in position for use, enlarged portions carried upon each of the clamping members, said enlarged portions having an opening therethrough whose walls are oppositely and outwardly flared, extensions carried by each of the clamping members having calibrations adapted to cooperate with the calibrations upon the square, an arm pivoted at one end within the single cut-out portion of one of the enlarged portions for sliding movement through the opening of the remaining enlarged portion and having graduations thereon, and one of the clamping members having indicia thereon to cooperate with the adjacent edge of the arm to determine the pitch of a rafter whose length is indicated upon the arm.

In testimony whereof I affix my signature.
60 HARRY H. FERRIS.
